FIG. 1 is a front view of a first image of a first embodiment of a display screen portion with animated graphical user interface showing my new design;

FIG. 2 is a front view of a second image thereof;

FIG. 3 is a front view of a third image thereof;

FIG. 4 is a front view of a first image of a second embodiment of a display screen portion with animated graphical user interface showing my new design;

FIG. 5 is a front view of a second image thereof; and,

FIG. 6 is a front view of a third image thereof.

In the first embodiment, the appearance of the transitional image sequentially transitions between the images shown in FIGS. 1 through 3. In the second embodiment, the appearance of the transitional image sequentially transitions between the images shown in FIGS. 4 through 6. The process or period in which one image transitions to another image forms no part of the claimed design. The broken line showing of a display screen and remainder of the graphical user interface forms no part of the claimed design.

The greyscale indicates a contrast of appearance.
